UNITED STATES PATENT OFFICE.

ERNEST F. DAVIS, OF MUNCIE, INDIANA, ASSIGNOR TO WARNER GEAR COMPANY, OF MUNCIE, INDIANA, A CORPORATION OF INDIANA.

HEAT-DRAWING FURNACE.

Application filed June 16, 1926. Serial No. 116,300.

My invention relates to furnaces and particularly that type of furnace for heat treating wherein the articles to be treated are immersed in a bath of oil. The invention is particularly applicable to furnaces for heat treating hardened work such as steel gears and the like, for drawing the temper thereof by immersing the same in a bath of heated oil in the manner commercially known as oil drawing.

It is one of the objects of my invention to provide a furnace of the above type wherein the mechanical handling of the articles may be reduced to a minimum and wherein the uncertainty of the time element in drawing the temper of hardened work may be eliminated.

In the drawings illustrating certain embodiments of my invention.

Fig. 1 is a side elevation partly in section of a furnace embodying my invention;

Fig. 2 is a plan view of another form of furnace embodying my invention, and

Fig. 3 is a longitudinal sectional view thereof.

In the embodiment illustrated in Fig. 1 I provide a cylindrical open topped oil tank 1 which is adapted to be surrounded by suitable insulating material 2 in turn surrounded 30 and covered by a metallic cover or casing 3. This tank at its top edge is provided with a hollow sill 4 having an internal skirt 5 which projects down into the tank slightly below the oil level. The tank is adapted to be filled 35 with oil to about the level indicated in which the material to be treated is adapted to be immersed. This oil is maintained at a proper temperature by controllable heating units 6 of a type well known in the commercial art, which units are supported on the sides of the 40 tank at suitable intervals, being arranged more closely together at the entry point in the tank, that is, at the point where the cold articles are introduced. These heating units are connected by suitable circuits 7 with the 45 instruments of control 8 by which the supply of current may be readily varied either manually or automatically through the medium of automatic thermostats in a manner well known to maintain the temperature of the oil at a given point.

Overhanging the tank is a suitable frame 9 from which is supported a bull wheel 10 provided on its rim with suitable hooks 11 or 50 openings 12. The hooks or openings provide

means for attaching to the wheel supporting hangers 13 by which the work to be treated may be supported in an immersed condition in the oil bath. This wheel is provided with a hub 14 mounted on a shaft 15 hung in a bearing on the top member of the frame 9 and this shaft at its upper end may be provided with a driving pulley 16 belted or otherwise connected with a power motor 17. The bottom end of the shaft is provided with 65 an extension 18 provided at its lower end with a propeller or agitator 19 by which during the rotation of the bull wheel the oil is sufficiently agitated or circulated past the heaters in order to maintain an even temperature of the oil throughout its mass. A suitable casing or cover 20 closes the top of the tank which casing is provided with an opening 21 to permit the insertion and removal of the articles to be immersed.

The agitation of the oil not only causes a circulation of the same past the heating units to thereby maintain an even temperature throughout the mass but also assists in preventing the accumulation of sludge and carbon on the heating units, which accumulation would reduce the efficiency of the units. Furthermore, by the hanging of the heating units on the sides of the tank instead of placing them in the bottom of the tank, the sludge and 85 carbon will be precipitated away from the units instead of on them as would be the case if they were located in the bottom of the tank. The hanging of the units on the side of the tank permits a more ready removal of the 90 units for cleaning and inspection than if they were placed in the bottom of the tank.

In the structure illustrated in Figs. 2 and 3 I have shown another form of furnace which may be used advantageously. In this form I preferably provide an elongated tank 22 surrounded by suitable insulation 23 covered by an enclosing casing 24. This tank is likewise provided with the heating units 6 having the control circuit 7 connecting the 100 same with the controlling instrument board 8 as is the case in the structure illustrated in Fig. 1.

For immersing the materials to be treated in an oil bath I provide a conveyor 25 preferably of the chain type in the form of a continuous belt and provided at suitably spaced intervals with agitating paddles or projections 26. This conveyor travels over an idler sprocket or pulley 27 on a shaft 28 at one end 105 110

of the tank and over a suitable driving sprocket or pulley 29 on a suitable shaft 30 at the opposite end of the tank, which shaft is adapted to be driven by any suitable power means. The length of the conveyor is such that there is considerable sag in the top run of the conveyor so that as the articles are placed thereon they will be carried well beneath the oil level and be completely immersed in the oil of the tank. The paddles or projections 26 serve to agitate the oil for the same purpose as that of the agitator 19 in the structure illustrated in Fig. 1.

While I have spoken of the liquid in the tank as being oil it will be understood that any other suitable material for the purpose may be used and where I have referred in the specification and claims to oil it will be understood that this term is sufficiently comprehensive to include other liquids which may be used for similar purpose.

I claim as my invention:

1. In an oil drawing furnace the combination with a tank constructed to contain oil and surrounded by insulating material, of controllable electric heating units arranged in said tank and immersed in the oil for heating said oil, progressively moving carrier means for supporting the work immersed in said oil and progressively moving the same through the tank and means for imparting a circulatory movement to the oil to cause the same to circulate over the heating units.
2. In an oil drawing furnace the combination with a tank constructed to contain oil and surrounded by insulating material, of controllable electric heating units supported

against the sides of the tank immersed in the oil for heating said oil, progressively moving carrier means for supporting the work immersed in said oil and progressively moving the same through the tank and means for imparting a circulatory movement to the oil to cause the same to circulate over the heating units.

3. In an oil drawing furnace the combination with a circular tank constructed to contain oil and surrounded by insulating material, a wheel mounted above said tank to rotate in a horizontal plane, means for supporting the work to be treated from said wheel immersed in the oil in the tank, controllable heating units arranged in said tank and immersed in the oil and means for imparting a circulatory movement to the oil to cause the same to circulate past the heating units.

4. In an oil drawing furnace the combination with a circular tank constructed to contain oil and surrounded by insulating material, of a wheel mounted above said tank and rotating in a horizontal plane, means for supporting work from said wheel immersed in the oil in the tank, controllable heating units supported on the sides of said tank and means for imparting a circulatory movement to the oil in the tank to cause the same to circulate past the heating units.

In witness whereof, I, ERNEST F. DAVIS, have hereunto set my hand at Muncie, Indiana, A. D. one thousand nine hundred and twenty-six.

ERNEST F. DAVIS.
